(57) CLAIM

I claim the ornamental design for a collapsible yoga storage bench, as shown and described.

DESCRIPTION

FIG. 1 is a bottom perspective view of a collapsible yoga bench, showing my new design in an extended configuration; FIG. 2 is a top perspective view of FIG. 1;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view of FIG. 1;

FIG. 7 is a bottom plan view of FIG. 1; and,

FIG. 8 is a bottom perspective view thereof, illustrated in a collapsed configuration.

The broken lines showing a person, a carrying strap and a rolled yoga mat in FIG. 1 depict environmental matter and form no part of the claimed design.
